BLOUSE

Jennie Brown, Red Bay, Ala.

Application May 29, 1945, Serial No. 596,563

12 Claims. (Cl. 2—105)

1

This invention relates to new and useful improvements in blouses.

More particularly, the invention proposes a new and improved blouse which is characterized by the fact that it is formed from a flat strip of cloth material for wrapping about the body at the blouse region and having cutout flap-like portions forming arm openings and shoulder portions. It is also contemplated to provide drawstrings mounted along the top and bottom edges of said flat strip for gathering the top and bottom portions of the blouse for adjusting the sizes of the neck and waist.

The invention contemplates numerous modified forms and variations, each and all embodying the essential features thereof. In one form it is proposed that the flat strip be rectangularly shaped. In another form it is proposed that the flat strip be arcuately shaped. In still another form it is proposed that sections be cutout from the strip beneath the armpits and that these open areas be closed with laces or tie strings. The invention also contemplates constructions in which the blouse is open at the back, or open at the front, depending merely on design. A construction is also suggested for increasing the neck opening at the front of the blouse.

The dominating feature of the new and improved blouse resides in the fact that it may be opened and laid flat so that it may be easily laundered and ironed. A great variety of trimmings and decorations may be employed in conjunction with the basic foundation pattern already suggested.

Another object of the invention is the construction of a blouse as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front elevational view of a blouse constructed in accordance with this invention.

Fig. 2 is a rear elevational view of the blouse shown in Fig. 1.

Fig. 3 is an elevational view of the blouse shown in Figs. 1 and 2 opened into a flat condition.

Fig. 4 is an elevational view of a modified form of the blouse illustrated in an open or flat condition.

2

Fig. 5 is a developed view of the blank, or pattern used for constructing the blouse illustrated in Fig. 4.

Fig. 6 is a front view of a blouse constructed in accordance with another form of this invention.

Fig. 7 is a developed view of the blank, or pattern used for constructing the blouse shown in Fig. 6.

Fig. 8 is a front elevational view of still another blouse embodying still another form of this invention.

Fig. 9 is a plan, or developed view of the pattern used in constructing the blouse shown in Fig. 8.

Fig. 10 is a front elevational view of still another blouse embodying another form of this invention.

Fig. 11 is a perspective view of the blouse shown in Fig. 10 in an open condition but rolled around into circular form.

Fig. 12 is the blank, or pattern used in constructing the blouse shown in Figs. 10 and 11.

Fig. 13 is a front elevational view of still another blouse embodying another form of the invention.

Fig. 14 is an elevational view of the blouse shown in Fig. 13 opened into a flat condition.

The blouse, in accordance with that form of

the invention illustrated in Figs. 1-3 inclusive, includes a flat strip 10 of cloth material for wrapping around the body at the blouse region and having cutout flap-like portions 11 forming arm openings and shoulder portions for the blouse.

Drawstrings 12 are mounted along the top and bottom edges of the strip 10 for gathering the top and bottom portions of the blouse for adjusting the sizes of the neck and waist. The drawstrings 12 are engaged through hems 14 formed along the top and bottom edge portions of the strip 10. Short lines of stitches 15 are engaged through the top and bottom center points of the flat strip 10 and serve to hold the drawstrings 12 from coming out of the hems 14.

The flat strip 10 is rectangularly shaped. Suitable trimmings and decorations may be applied to the flat strip portion for ornamenting the blouse. The drawstrings 12 may be of non-elastic material, or of elasticized material if it is desired that the resiliency serve to naturally gather the top and bottom portions of the blouse.

The blouse, as illustrated in Fig. 3, may be converted to the form shown in Figs. 1 and 2 by merely gathering the top and bottom portions of the flat strip 10 by pulling the drawstrings 12 and

pushing the edge portions of the flat strip 10 and tying the drawstrings into bows at the back of the blouse.

In Figs. 4 and 5 another embodiment of the invention has been disclosed. In this form of the invention the blouse has a flat strip 10 which is arcuately shaped and arranged with the larger dimension across the top.

In other respects this form of the invention is similar to that previously shown and like reference numerals identify like parts in each of the several views.

In Fig. 5 a blank or pattern is shown for constructing the blouse shown in Fig. 4. It should be noted that the pattern or blank is rectangularly shaped. However, it is provided with cutouts 16 extending from the cutout flap-like portions 11 down to the bottom edge. These cutouts 16 are tapered so that when their adjacent edges are sewed together, as shown in Fig. 4 they serve to give the flat strip 10 its arcuate shape.

In Figs. 6 and 7 another embodiment of the invention is shown which is very similar to the first form, but distinguishes in the fact that cutouts 17 are provided beneath the flap-like portions 11. These cutouts extend from the armpits to the bottom edge of the flat strip 10. Buttonholes 18 are arranged along the sides of the cutouts 17. A lace 19 is engaged through the buttonholes 18 for restricting the cutouts 17.

In other respects this form of the invention is similar to that previously shown and like reference numerals identify like parts in each of the several views.

In Fig. 7 the blank or pattern is shown for constructing the blouse shown in Fig. 6. It must be recognized that in the finished article the usual drawstrings must be mounted along the top and bottom edges of the strip 10.

In Figs. 8 and 9 still another form of the invention is shown which is very similar to the form shown in Figs. 6 and 7, distinguishing merely in the fact that tie strings 20 are provided for restricting the openings 17.

In Figs. 10-12 still another form of the invention is shown in which the blouse is open at the front. The particular blouse is formed from a flat strip 22 consisting of two adjacent sections 23 which are stitched together by a line of stitches 24 at the back of the blouse.

The open front of the blouse is provided with tie strings 25. In other respects this blouse is identical to the one shown in Figs. 1-3.

In Figs. 13 and 14 still another form of the invention is shown which is very similar to the blouse shown in Figs. 1-3, distinguishing merely in the fact that the strip 10 has a cutout 26 at the front to increase the neck cutout of the blouse.

In other respects this form of the invention is similar to that previously shown and like reference numerals identify like parts in each of the several views.

The dominating feature of each and all of the blouses described in this specification resides in the fact that when opened they may be laid flat and therefore easy to launder.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new and desire to secure by United States Letters Patent is:

1. A blouse, comprising a flat strip of cloth material for wrapping about the body at the blouse region so that the ends of the material meet at the back of the wearer and having rectangular cutout flap-like portions forming arm openings and shoulder portions, and drawstrings mounted along the top and the bottom edges of said strip for gathering the top and bottom portions of the blouse for adjusting the sizes of the neck and waist and for closing the rear meeting edges of the material at the top and bottom of the garment.
2. A blouse, comprising a flat strip of cloth material for wrapping about the body at the blouse region and having rectangular cutout flap-like portions forming arm openings and shoulder portions, and drawstrings mounted along the top and the bottom edges of said strip for gathering the top and bottom portions of the blouse for adjusting the sizes of the neck and waist, said flat strip being rectangularly shaped.
3. A blouse, comprising a flat strip of cloth material for wrapping about the body at the blouse region and having rectangular cutout flap-like portions forming arm openings and shoulder portions, and drawstrings mounted along the top and the bottom edges of said strip for gathering the top and bottom portions of the blouse for adjusting the sizes of the neck and waist, said flat strip being arcuately shaped.
4. A blouse, comprising a flat strip of cloth material for wrapping about the body at the blouse region and having rectangular cutout flap-like portions forming arm openings and shoulder portions, and drawstrings mounted along the top and the bottom edges of said strip for gathering the top and bottom portions of the blouse for adjusting the sizes of the neck and waist, said flat strip being arcuately shaped, and arranged with the major dimension at the top.
5. A blouse, comprising a flat strip of cloth material for wrapping about the body at the blouse region and having rectangular cutout flap-like portions forming arm openings and shoulder portions, and drawstrings mounted along the top and the bottom edges of said strip for gathering the top and bottom portions of the blouse for adjusting the sizes of the neck and waist, said flap strip having cutouts extending downwardly from the lower edge of the flap-like cutouts to the bottom thereof.
6. A blouse, comprising a flat strip of cloth material for wrapping about the body at the blouse region and having rectangular cutout flap-like portions forming arm openings and shoulder portions, and drawstrings mounted along the top and the bottom edges of said strip for gathering the top and bottom portions of the blouse for adjusting the sizes of the neck and waist, said flat strip having cutouts extending from the armpits to the bottom thereof, the material forming the sides of these cutouts being sewed together to give said flat strip an arcuate shape.
7. A blouse, comprising a flat strip of cloth material for wrapping about the body at the blouse region and having rectangular cutout flap-like portions forming arm openings and shoulder portions, and drawstrings mounted along the top and the bottom edges of said strip for gathering the top and bottom portions of the blouse for adjusting the sizes of the neck and waist, said flat strip having cutouts extending

downwardly from the lower edge of the flap-like cutouts to the bottom thereof, the material along the sides of said latter cutouts being provided with buttonholes, and drawstrings laced through said buttonholes.

8. A blouse, comprising a flat strip of cloth material for wrapping about the body at the blouse region and having rectangular cutout flap-like portions forming arm openings and shoulder portions, and drawstrings mounted along the top and the bottom edges of said strip for gathering the top and bottom portions of the blouse for adjusting the sizes of the neck and waist, said flat strip having cutouts extending downwardly from the lower edge of the flap-like cutouts to the bottom thereof, said latter openings being restricted with tie strings.

9. A blouse, comprising a flat strip of cloth material for wrapping about the body at the blouse region and having rectangular cutout flap-like portions forming arm openings and shoulder portions, and drawstrings mounted along the top and the bottom edges of said strip for gathering the top and bottom portions of the blouse for adjusting the sizes of the neck and waist, said blouse having its opening at the front.

10. A blouse, comprising a flat strip of cloth material for wrapping about the body at the blouse region and having rectangular cutout flap-like portions forming arm openings and shoulder portions, and drawstrings mounted along the top and the bottom edges of said strip for gathering the top and bottom portions of the blouse for adjusting the sizes of the neck and waist, said blouse having its opening at the rear.

11. A blouse, comprising a flat strip of cloth material for wrapping about the body at the blouse region and having rectangular cutout

flap-like portions forming arm openings and shoulder portions, and drawstrings mounted along the top and the bottom edges of said strip for gathering the top and bottom portions of the blouse for adjusting the sizes of the neck and waist, said flat strip having its top edge at the center thereof cut out to form a larger neck opening at the front of the blouse.

12. A blouse comprising a flat strip of cloth material for wrapping about the body at the blouse region and having cutout flap-like portions forming arm openings and shoulder portions, and draw strings mounted along the top and bottom edges of said strip for gathering the top and bottom portions of the blouse for adjusting the sizes of the neck and waist, stitching adjacent the bottom and top portions of the blouse for holding said draw strings in place, said flat strip having cutouts extending downwardly from the lower edge of the flap-like cutouts to the bottom thereof, the material along the sides of said latter cutouts being provided with button holes, and draw strings placed through said button holes.
